UNITED STATES PATENT OFFICE.

BRUCE C. WHITE, OF NEW YORK, N. Y.

MULTICOLOR-PRINTING PRESS.

1,426,431.

Specification of Letters Patent. Patented Aug. 22, 1922.

Application filed August 3, 1920, Serial No. 401,011. Renewed November 29, 1921. Serial No. 518,713.

To all whom it may concern:

Be it known that I, BRUCE C. WHITE, a citizen of the United States, and resident of New York, in the county of New York, 5 and State of New York, have invented certain new and useful Improvements in Multi-color-Printing Presses, of which the following is a specification.

This invention relates to improvements in 10 multi-color printing presses in which rotating couples are employed to print two or more colors in superimposed relation upon sheets, having particular reference to a type of press shown and described in Patent No. 1,146,039 dated July 13, 1915, and Patent No. 1,306,086 dated June 10, 1919.

In the press disclosed in the last mentioned patent the sheet to be printed is carried between the printing couples, comprising type 20 cylinders and impression cylinders, by carrier rings which enclose the latter. In the arrangement disclosed in this patent the sheet, while being fed between a pair of cylinders, had a tendency to be moved prematurely against the type cylinders by the air set up, the surface of the impression cylinders tending to develop an air pressure by reason of its lack of lateral or circumferential passages or depressions as compared 25 with the type cylinders resulting at times in the smearing or improper printing of the sheet by its being forced against the type cylinders prematurely.

The present invention has for its main 30 object to prevent this movement of the sheet toward the type cylinders, more specifically the invention having for an object to provide a novel arrangement of suction means for preventing the formation of an air cushion or air pressure which would tend to 35 throw the sheet against the type cylinders.

For full comprehension of the invention, and of the objects and advantages thereof, reference will be had to the following description 40 and accompanying drawings, and to the appended claims in which the various novel features of the invention are more particularly set forth.

Fig. 1 of the drawings is a longitudinal 45 vertical sectional view of a multi-color printing press having the invention applied thereto.

Fig. 2 is a detail transverse view showing a modification of the suction device.

50 In the drawings the bed plate of the press is indicated at 1 and has mounted thereon

the front and rear side frames 3. In these frames suitable bearings are provided in which are journaled for rotation the two printing couples composed of the type or 60 plate cylinders 4 and 5 and the impression cylinders 6 and 7 which are adapted to engage, for printing action, the impression surfaces of the cylinders 6 and 7 which are conventionally arranged with draw and filling sheets to afford means for applying the necessary packing or "make ready."

The work to be printed is advanced by means of a sheet-carrier composed of a pair of toothed carrier-rings 16 (only one of 70 which is shown) the axes of the four cylinders and the carrier-rings being preferably arranged in one horizontal plane, the carrier-rings being internally toothed and adapted to engage gear-rings at one end of 75 the two impression cylinders. The carrier-rings are provided with a series of cross-braces or sheet carriers 17 spaced equidistant thereabout, these cross-braces being external to the path of the sheet, a sheet support 33 and supporting plates 34 and 35 being provided for carrying the sheet from printing couple to printing couple. The sheet is supported, while passing under the impression cylinders from one couple to the 80 other, by an arcuate suction box 36 to which is connected a pipe 37 leading from any suitable suction device. These parts as thus described are all constructed and operated as 85 fully shown and described in the Patent 90 No. 1,306,086 above referred to.

According to the present invention I provide between the impression cylinder 6 and the adjacent plate 34 a suction box 40 which is preferably of wedge shape to fit between 95 the converging surfaces of the plate and cylinder. The outer wall of this box may be formed by the plate 34, the inner wall being formed by a second plate 41, which is convexed inwardly toward the body of 100 the box. These plates 34 and 41 are slightly separated at their converging or forward ends to provide an air intake opening. From the rear end of the box 40 a baffle plate 42 extends directly toward the cylinder 6. A 105 pipe 43 leads from the box 40 to the suction pipe 37 before referred to, this pipe having a valve 44 thereon whereby the force of the suction exerted may be regulated.

With this arrangement the air is exhausted 110 from the converging space between the type and impression cylinders, while at the

same time the direction of the exhaustion of the air is away from the type cylinder so that any tendency of the sheet to be moved toward the type cylinder is prevented.

- 5 I may either leave the plate 34 solid as shown in Fig. 1 or may form the portion thereof extending below the pipe with a series of perforations 45, as shown in Fig. 2. With this arrangement the suction acts 10 to keep the sheet in contact with the plate 34 and prevent the same folding over on the type cylinder 4 when the press stops, and as the openings in the plate are closed by the sheet while passing over the latter, the force 15 of the suction exercised at the lower edge of the plate is not diminished.

What I claim is as follows:

1. In a printing press of the type described, co-operating type and impression cylinders, an annular carrier device enclosing the impression cylinder, and a wedge shaped suction box located between said impression cylinder and carrier device, the adjacent edges of the converging side walls of 20 said suction box being spaced apart and forming an air inlet to exhaust the air from the converging space between said impression cylinder and carrier device.
2. In a printing press of the type described, co-operating type and impression cylinders, an annular carrier device enclosing the impression cylinder, a wedge shaped suction box located between said impression cylinder and carrier device, the adjacent 25 edges of the converging side walls of said suction box being spaced apart to form an air inlet, and a baffle device extending from said suction box to a point adjacent said impression cylinder.
3. In a printing press of the type described, co-operating type and impression cylinders, an annular carrier device enclosing the impression cylinder, a wedge shaped suction box located between said impression cylinder and carrier device and having the adjacent edges of the converging side walls thereof spaced apart to form an air inlet, the outer of said side walls being perforated and disposed in the path of said carrier device to support the sheet to be printed, and a baffle device extending from said suction box to a point adjacent said impression cylinder.
4. In a printing press of the type described, co-operating type and impression cylinders, an annular carrier device enclosing the impression cylinder, and a wedge shaped suction box located between said impression cylinder and carrier device and 50 having the adjacent edges of the converging side walls thereof spaced apart to form an

air inlet, the outer of said side walls being perforated and disposed in the path of said carrier device.

5. In a printing press of the type described, co-operating type and impression cylinders, an annular carrier device enclosing the impression cylinder, a segmental plate co-operating with and concentric to said carrier device, a suction box located between said plate and the impression cylinder, and a baffle plate extending from said suction box toward the impression cylinder. 65

6. In a printing press, co-operating type and impression cylinders, a suction device 70 located between said cylinders and having converging side walls, the adjacent edges thereof being spaced apart and forming an air inlet to exhaust the air from the converging space between said cylinders.

7. In a printing press, co-operating type and impression cylinders, a suction device 75 located between said cylinders and having converging side walls, the adjacent edges thereof being spaced apart to form an air inlet, 80 and a baffle device extending from said suction device to a point adjacent said impression cylinder.

8. In a printing press, co-operating type and impression cylinders, a suction device 85 located between said cylinders and having converging side walls, the adjacent edges thereof being spaced apart to form an air inlet, the outer of said side walls being perforated and disposed to support the sheet 90 to be printed in the path of its movement, and a baffle device extending from said suction device to a point adjacent said impression cylinder.

9. In a printing press, co-operating type 100 and impression cylinders, sheet feeding means co-operating with said cylinders, a suction device located between said impression cylinder and the sheet feeding means, said suction device including a support for 105 the sheet, and an air inlet leading into said suction device independently of said support and adapted to withdraw the air from between said impression cylinder and the sheet to be printed.

10. In a printing press, co-operating type and impression cylinders, means for supporting the sheet in its path of movement, and means for withdrawing the air from between said impression cylinder and said 110 sheet supporting means independently of said supporting means.

Signed at New York, in the county of New York and State of New York, this 29th day of July A. D. 1920.

BRUCE C. WHITE.
